CLAIM

The ornamental design for a flat fuse holder, as shown and described.

DESCRIPTION

FIG. 1 is a perspective view of a flat fuse holder embodying the present design, showing the device in its capped position;

FIG. 2 is a perspective view thereof, shown in its uncapped position;

FIG. 3 is a top plan view of a flat fuse holder showing my new design in the capped position;

FIG. 4 is a bottom plan view thereof;

FIG. 5 is a right side elevational view thereof;

FIG. 6 is a left side elevational view thereof;

FIG. 7 is a front elevational view thereof; and

FIG. 8 is a rear elevational view thereof.
